UNITED STATES PATENT OFFICE.

HAROLD W. MEADE, OF YEDDO, INDIANA.

WINDOW-OPERATING DEVICE.

Application filed July 24, 1922. Serial No. 577,168.

To all whom it may concern:

Be it known that I, HAROLD W. MEADE, a citizen of the United States, residing at Yeddo, in the county of Fountain and State of Indiana, have invented new and useful Improvements in Window-Operating Devices, of which the following is a specification.

This invention relates to window operating devices and has for its object the provision of an electrically operated mechanism designed for association with the windows of buildings, railroad coaches, street cars and the like, whereby a person may simply by pressing a push button cause the window to be opened or closed at will and without the exercise of any manual effort whatever.

An important object is the provision of a device of this character which is electric motor driven and which embodies electro-magnetically actuated clutch means for selecting the direction of movement of the mechanism so that the window will be either positively driven to open or closed position.

A further object is the provision of a mechanism of this character which is provided with automatic circuit breaking means which will come into play when the window reaches its maximum open or closed position for breaking the circuit and rendering the mechanism inoperative until the other button is pressed to reverse the movement.

An additional object is the provision of a device of this character which will be comparatively simple in construction and installation, highly efficient and positive in operation, durable in service and a general improvement in the art.

With the above and other objects and advantages in view the invention consists in the details of construction to be hereinafter more fully described and claimed and illustrated in the accompanying drawings in which:

Figure 1 is a view of a window showing it in closed position and showing such portion of the mechanism as is ordinarily visible,

Figure 2 is a view showing the window open and showing the casing for the mechanism in section, the clutch mechanism being at one limit of its movement,

Figure 3 is a vertical section, Figure 4 is a horizontal section,

Figure 5 is an enlarged plan view of the clutch control mechanism,

Figure 6 is a detail cross section,

Figures 7 and 8 are detail views of the electromagnet structure,

Figure 9 is a detail view of the switch.

Referring more particularly to the drawings the letter A designates a wall which might be the side of a building or the side of a railroad coach, street car or the like, B designates the window opening and C represents the window sash which is mounted for vertical sliding movement in the ordinary manner. In case the device is installed in connection with the windows of railroad coaches and the like it is obvious that there would be a series of windows each of which would be provided with my operating mechanism to be described though for purposes of illustration I have shown one window only as that is entirely sufficient to give a clear understanding of the construction and operation.

In carrying out my invention I provide a casing 20 which is let into the wall A at a point somewhat below the window opening. This casing is here shown as being rectangular in shape and has one end 21 and also its top 22 capable of removal to permit access to the interior for the purpose of adjusting or repairing the mechanism therein to be described. This casing is provided with attaching lugs 23 by means of which it may be securely anchored in place. Extending downwardly from the bottom of this casing are tubular housings 24 while located on the cover 22 directly in line with these housings are guides 25. Secured upon the edges of the sliding sash and recessed thereinto are rods 26 which are slidable through the guides 25 and which are adapted to be received within the housings 24 when the window is in lowered or open position. These rods may operate within telescopic guide tubes 27 and 28 which slide one within the other and which are connected respectively with the top of the casing and the bottom of the window frame for the purpose of enclosing the rods and protecting them against injury. The lower ends of these rods 26 are threaded, one having a right hand and the other a left hand thread.

Journalized longitudinally of the casing 20 is the main drive shaft 29 which is driven from an electric motor 30 of any conventional or preferred type. Rotatable upon

this shaft at substantially the center of the casing are clutch elements 31 and 32, the former of which carries a spur gear 33 and the latter of which carries a sprocket 34.

5 The remainder of the clutch mechanism will be described hereinafter.

Rising from the bottom of the casing 20 are standards 35 and 36 formed with bearings for a counter shaft 37 which carries a 10 spur gear 38 meshing with the gear 33 and which also carries a sprocket 39 about which is trained a chain 40 which is in turn trained about the sprocket 34. Secured upon the ends of the counter shaft 37 are beveled 15 gears 42 which mesh with beveled gears 43 carried by sleeves 44 journaled within the guides 25 on the cover 22 and within bearings 45 on the bottom of the casing. These sleeves are internally threaded, one with a 20 right hand and the other with a left hand thread and have screwing engagement with the threaded lower ends of the rods 26 so that when the counter shaft 37 is rotated in one direction or the other the intermeshing 25 beveled gears rotating the sleeves 44 will cause these sleeves to act as nuts to effect longitudinal movement of the rods 26 and consequently the window.

The clutch shifting mechanism comprises 30 a rod 46 which is slidable through bearing brackets 41 and which has one end carrying an adjustably mounted fork 47 fitting within a groove in a double ended clutch member 48 splined upon the shaft 29 between the pinion 33 and sprocket 34 thereon. This rod 46 carries two equalizing springs 49 and 50 as shown in the detail view and the free end of the rod carries an electromagnet 51 having its cores projecting beyond both ends 40 of its frame as shown. Mounted upon the end plate 21 is a horse shoe magnet 52 with which the electromagnet 51 co-operates and this horse shoe magnet may be of the permanent or electromagnetic type whichever may 45 be preferred or be found more advantageous.

The control mechanism includes a pair of push buttons 53 and 54 mounted upon the window casing and connected with a source of current 55 which might be of any type 50 but which, in case the device is used on a railroad coach, would undoubtedly be a dynamo. This source of current is connected with the motor 30 and electromagnet 51 as shown in the diagram so that when either 55 push button is pressed the circuit will be closed through the motor and also through the electromagnet 51, it being however to be noted that when one push button is pressed the current will flow through the electromagnet 51 in a direction opposite to the flow when the other push button is pressed.

I prefer to provide a circuit breaking device which will operate automatically by the sash when the latter is moved to its entirely 60 open or entirely closed position. This cir-

cuit breaking mechanism includes a support 56 carrying contacts 57 normally engaged by other contacts 58 carried by a resilient strip 59, these various contacts being connected in the circuit as shown in the diagram. Disposed in the path of movement of the window are plungers 60 engaged by the window at the ends of the movement thereof and operating to force the resilient strip 59 away from the support 56 and consequently move the contacts 58 away from the contacts 57 for automatically breaking the circuit.

In the operation, assuming that the window is closed, to effect opening thereof the operator presses upon the push button 54 whereupon the circuit will be closed from the source of current through the motor 30 and electromagnet 51. The wiring is so arranged that the polarity of the electromagnet 51 when energized in this instance will be opposed to the polarity of the permanent magnet 52 and this will cause repulsion which will result in longitudinal shifting of the rod 46 and fork 47. This movement will cause the clutch member 48 to engage the clutch member 31 and lock the pinion 33 onto the shaft 29. As the shaft 29 is rotated by the motor 30 and as the pinion 33 meshes with the pinion 38, the counter shaft 37 will be driven and the beveled gears 42 will operate to rotate the sleeves 44 and these sleeves being formed as nuts and being threaded upon the rods 26 will cause these rods to be drawn downwardly into the housing 24, carrying the window sash downwardly with them. The telescopic guide tubes 27 and 28 will slide one within the other as this movement occurs, so as not to interfere with the action. Upon reaching its lowermost position the window sash will engage one of the plungers 60 and break the circuit by moving the contact 58 away from the contact 57 so that the motor will cease to operate, as otherwise damage might be done if the operator did not remove his finger from the push button at the proper time.

Assuming that the window has been thus opened, when it is desired to close it, the operator presses the button 53, whereupon the motor will again be energized as will be also the electromagnet 51, but in this instance the polarity of the magnet 51 is reversed so that there will be an attraction between its core and the magnet 52 which will result in moving the rod 46 lengthwise but in a direction opposite to that of the movement first described. The fork 47 will then operate to slide the double ended clutch member 48 into engagement with the clutch element 32 and this will lock the sprocket 34 onto the shaft 29. As the shaft 29 is rotated by the motor 30 the chain 40 trained about the sprocket 34 will drive the sprocket 39 and consequently the counter shaft 37 in 130

a direction opposite that of the first described action so that the gears 42 meshing with the gears 43 will turn the nut members 44 in the reverse direction. This movement of these nut members or sleeves 44 will cause longitudinal movement of the rods 26 upwardly, carrying the window sash with them. Upon reaching its entire closed position the window will engage the other 10 plunger 60 and break the circuit between the contacts 57 and 58.

From the foregoing description and a study of the drawings it will be apparent that I have thus provided a simply constructed and easily installed mechanically operated and electrically controlled mechanism for opening and closing windows either locally or from a distant point, if preferred, depending upon the nature of the 20 building where the windows are located and depending upon various other conditions and circumstances. It is to be noted that the various parts are adjustably mounted so as to take care of variations and conditions which may arise from time to time either during installation or after installation. The provision of the automatic circuit breaker is an important feature as it prevents too long operation of the mechanism which would result in damage to some or all of the parts. The device is efficient in every way and will consequently work as an improvement as making manual effort unnecessary.

35 While I have shown and described the preferred embodiment of the invention it is of course to be understood that I reserve the right to make such changes in the form, construction and arrangement of parts as 40 will not depart from the spirit of the invention or the scope of the subjoined claims.

Having thus described my invention I claim:

1. Means for operating a slidably mounted window comprising a casing, threaded rods secured to the window and slidably transversely of the casing, a drive shaft journaled longitudinally of the casing, an electric motor for rotating said shaft, and 45 normally inactive, nut members within the casing threaded on the said rods and carrying beveled gears, a counter shaft carrying beveled gears meshing with said first named gears, a pair of drive connections between the drive shaft and the counter shaft and selectively operable to rotate said counter shaft in either direction, clutch means for throwing either drive connection into operation, a longitudinally movable rod forming part of said clutch means, electromagnetic means for moving said last named rod lengthwise in either direction, and a pair of 50 control switches connected in circuit with a

source of current, said motor and said electromagnetic means, and a pair of automatic 65 circuit breakers included in the circuit and located in the path of movement of the window for breaking the circuit when the window reaches either limit of its movement. 70

2. In means for operating a slidably mounted window, a stationarily mounted casing, threaded rods rigidly secured at opposite sides of the window and extending through said casing, nut members rotatably 75 mounted and threaded upon said rods and constrained against longitudinal movement, a drive shaft within the casing, a driven shaft operatively connected with said nut members for rotating the same, a longitudinally shiftable rod carrying a fork, a clutch member engaged by said fork and splined upon said driven shaft, clutch elements engageable by said first named clutch member for effecting rotation of the driven 80 shaft in one direction, and the electromagnetic means for shifting said rod. 85

3. Means for operating a slidably mounted window comprising threaded rods secured to the window at opposite sides thereof, a drive shaft, an electric motor for rotating said shaft and normally inactive nut members threaded on said rods and carrying bevel gears, a countershaft carrying bevel gears meshing with said first named 90 bevel gears, a pair of drive connections between the drive shaft and the countershaft and selectively operable to rotate said countershaft in either direction, a longitudinally 95 movable rod operating clutch means for throwing either drive connection into operation, electromagnetic means for moving said last named rod lengthwise in either direction, and a pair of control switches connected in circuit with a source of current, 100 said motor and said electromagnetic means. 105

4. Means for operating a slidably mounted window, comprising threaded rods secured to and depending from the window, a drive shaft, an electric motor for rotating said shaft, nut members threaded on said rods and carrying bevel gears, a counter-shaft carrying bevel gears meshing with said first named gears, spur gears on said shafts for rotating the same in opposite directions, a chain and sprocket connection between said shafts for rotating the same in both directions, and electromagnetically operated means for throwing either the spur gear connection or the sprocket and chain drive connection into operation for controlling the direction of rotation of said counter-shaft. 110 115 120

In testimony whereof I affix my signature.

HAROLD W. MEADE.
